DOLL

John S. Gilbraith, Ira, Ohio

Application January 24, 1939, Serial No. 252,610

3 Claims. (Cl. 46—141)

This invention relates to dolls.

A general object of the invention is to provide a doll having means for exuding liquids therefrom when a portion of the doll is compressed.

A particular object of the invention is to provide a doll of simple, inexpensive construction having novel means therein for exuding liquid at the eyes thereof in simulation of the act of crying tears.

Another object of the invention is to provide a doll which will exude liquid from the eyes, in simulation of the act of crying tears, when a portion of the doll is compressed or spanked.

Another object of the invention is to provide a doll which after having been fed a quantity of liquid at the mouth thereof will exude liquid from the lower body portion thereof, and will also exude liquid from the eyes in simulation of tears, when compressed or spanked.

Other objects of the invention will be manifest from the following brief description and the accompanying drawing.

Of the accompanying drawing:

Figure 1 is a rear view, partly broken away and in section, of a doll having the improved structure embodying the invention incorporated therewith.

Figure 2 is a cross-section substantially on line 2—2 of Figure 1.

Figure 3 is a cross-section on line 3—3 of Figure 1.

Figure 4 is an enlarged fragmentary detail, partly in section, of the check valve in collapsed or closed condition for preventing return of liquid through the feed pipe to the mouth of the doll.

Figure 5 is a view similar to Figure 4, but further sectioned to show the valve in condition to allow passage of fluid to the fluid receptacle.

Figure 6 is a fragmentary view of a portion of the doll's face showing location of the tear ducts adjacent the corners of the eyes.

Referring to Figures 1 and 2 of the drawing, the numeral 16 may be a hollow torso of flexible or resilient material, such as rubber, and having a male neck joint 11 for a ball and socket connection with a preferably hollow head 12, the latter being retained on the torso by an integral flange 13. Legs 14, 14 and arms 15, 15 may be attached to the torso in any suitable manner.

A preferably relatively flat receptacle 16 of impervious, elastic or resilient material, such as rubber, may be mounted within the torso and retained against the back wall thereof by any suitable means, as for example by means of lugs 17,

17 and a rib integral with the wall of the torso. A relatively stiff or rigid plate 18 may be inserted between receptacle 16 and lugs 17 to provide a backing for the receptacle when it is squeezed or compressed for purposes subsequently to be described.

Extending downwardly from a mouth opening 19 in head 12 may be a conduit or feed pipe 20, the other end of which is attached to the inner wall of receptacle 16 and communicates with the interior thereof. Conduit 20 preferably extends into receptacle 16 to have attached thereto a check valve 21. This check valve may comprise a relatively small, thin rubber, bag or sac 22 attached to the end of conduit 20 at 23 in any suitable manner, and is provided with a small opening 24 for passage of fluid from conduit 20 into receptacle 16 by gravity. Bag 22 normally remains in collapsed condition, as shown in Figures 2 and 4, to prevent return of fluid back through conduit 20 from receptacle 16, and any additional internal pressure in the receptacle further tends to retain the valve 21 in the collapsed or closed condition. Fluid poured into mouth opening 19 flows into bag 22 to distend the same, as shown in Figure 5, allowing the fluid to pass through opening 24 and into receptacle 16.

A conduit 26 may be attached to receptacle 16, at a point beneath valve 21, to communicate with the interior of the receptacle, and may extend upwardly to communicate with the top of a relatively small chamber 27 within head 12, adjacent simulations of eyes 28, 28. A pair of ducts 29, 29 provide passages for fluid from a pocket 27, in the bottom of chamber 27, to the exterior of the head at points preferably at the corners of the eyes 28. A suitable opening 30 may be provided in the top of chamber 27 to prevent receptacle 16 from remaining collapsed when it is compressed to expel liquid therefrom. In addition opening 30 prevents the liquid from squirting from ducts 28 when receptacle 16 is compressed, by relieving the back pressure in chamber 27, and allows liquid trapped in pocket 27 to trickle through the ducts 28 after the pressure within receptacle 16 is released.

In the operation of the device water, or other fluid 25, is poured into mouth-opening 19 by any suitable method, as for example by applying the nozzle or nipple of a miniature baby feeding bottle 50 to the opening. This fluid passes by gravity into receptacle 16 through check-valve 21, the latter automatically closing when it becomes emptied of fluid. When fluid 25 has accumulated in the receptacle 16 pressure applied to the receptacle, 55

as by slapping or otherwise compressing the back wall of the torso 10 against the inherent yielding resistance thereof, will force quantities of the liquid through conduit 26 into the pocket 27^a of chamber 21, from which it will trickle slowly through the conduits 29 to exude in the form of tear-like drops at the corners of the eyes 28. When the receptacle 16 is thus compressed fluid is prevented from exuding from the mouth opening 19 by check-valve 21.

The features of the tear-crying doll may be combined with the features of a doll of the wetting type, by providing a relatively small opening 20^a in conduit 20 through which small quantities of the liquid poured into the mouth opening 19 may drop by gravity to a receptacle 32 in the bottom of the torso. The liquid in receptacle 32 upon reaching the level of a small hole 33 in the wall of the torso will trickle out in the usual manner of the wetting type doll.

It is understood that the torso 10 may be formed from a rigid material, but preferably is provided with a flexible area or an opening (not shown) adjacent the receptacle 16, so that the latter can be pressed against backing-plate 18 in the manner and for the purposes described.

Modifications of the invention may be resorted to without departing from the spirit thereof or the scope of the appended claims.

What is claimed is:

1. A doll comprising a torso, a head connected on said torso, said head having a mouth opening and simulations of eyes therein, a compressible receptacle for containing liquid in said torso and operable when compressed to force liquid therefrom, means for conveying liquid from said mouth opening to said receptacle, a relatively small vented chamber in said head having ducts extending therefrom to points adjacent said eyes, and means for conveying liquid from said receptacle to said chamber by compressing said receptacle, the liquid in said chamber thereby being relatively uncompressed and exuded in small

quantities through said ducts in simulation of crying-tears.

2. A doll comprising a hollow torso of yieldable, elastic, or resilient material, a head connected on said torso, said head having a mouth-opening and simulations of eyes therein, a compressible receptacle for containing liquid mounted in said torso to be compressed by applying yielding pressure to the torso adjacent said receptacle, means for supplying liquid from said mouth-opening to said receptacle, a valve associated with said supplying means for permitting liquid to flow therefrom by gravity into said receptacle but preventing return of said liquid through said supplying means, a relatively small vented chamber in said head having ducts extending to points adjacent said eyes, and means for conveying liquid from said receptacle to said chamber by compression of the receptacle, the liquid being relatively uncompressed in said chamber to exude by gravity through said ducts in simulation of crying-tears.

3. A doll comprising a hollow torso of yieldable, elastic, or resilient material, a head connected on said torso, said head having a mouth-opening and simulations of eyes therein, a compressible receptacle for containing liquid mounted in said torso to be compressed by applying yielding pressure to the torso adjacent said receptacle, means for supplying liquid from said mouth-opening to said receptacle, a valve associated with said supplying means for permitting liquid to flow therefrom by gravity into said receptacle but preventing return of said liquid through said supplying means, a relatively small vented chamber in said head having ducts extending to points adjacent said eyes, and means for conveying liquid from said receptacle to said chamber by compression of the receptacle, said liquid being relatively uncompressed in said chamber to exude by gravity through said ducts in simulation of crying-tears, said chamber having a vent opening therein above the normal liquid level therein.

JOHN S. GILBRAITH.
